UNITED STATES PATENT OFFICE.

NELS H. HASSEL, OF LOS ANGELES, CALIFORNIA.

RIVETING DEVICE.

1,309,134.

Specification of Letters Patent. Patented July 8, 1919.

Application filed June 20, 1918. Serial No. 241,066.

To all whom it may concern:

Be it known that I, NELS H. HASSEL, a citizen of the United States, residing at Los Angeles, in the county of Los Angeles and State of California, have invented a new and useful Riveting Device, of which the following is a specification.

My invention relates to the art of riveting, being more particularly a riveting tool which is supported and magnetically held against the plates in such a manner as to take up or cushion the jar of the tool during the riveting operation. In handling riveting tools the jar or impact of the tool is communicated directly to the operator to such an extent that such work is very fatiguing to the operator and eventually results in dismemberment of the operator for such work.

The principal object of my invention is to produce a riveting device of simple form and construction, in which the riveting tool proper is suspended or mounted elastically in a support, which during the riveting operation is magnetically held against the plates upon which the work is being performed.

Other objects and advantages will appear hereinafter from the following specification.

Referring to the drawings, which are for illustrative purposes only,

Figure 1 is a side elevation of the device, partly in section, embodying a form of my invention.

Fig. 2 is a face view of the device shown in Fig. 1, and

Fig. 3 is a general view of the device showing a bucking tool mounted in the support instead of the riveting tool proper.

11 designates a riveting tool having a body 12, a handle 13, and a hammer 14. In the form shown the tool is of the pneumatic type being supplied with air under pressure through a flexible connection indicated at 15, such air pressure being controlled as is usually done by a lever indicated at 16. The riveting tool is supported in a yoke, the body 12 of the tool extending through a circular opening 17 formed in a collar 18, which collar has formed thereon two arms 19 which extend outwardly and forwardly from the collar, each terminating in a foot 20. Each foot 20 is segmental in shape as shown in Fig. 2 and is hollowed out or recessed to form a pocket 21 to receive a winding 22 which is arranged about a core 23, the feet

forming electro-magnets for the purposes hereinafter described.

Each leg 19 of the yoke is hollow as indicated at 25 through which extend wires 26 and 27 from the respective windings 22 to a 60 socket 28 supported on one of the arms 19. The socket 28 is adapted to receive a plug 29 as diagrammatically shown in Fig. 1, the plug 29 being connected through wires 30 and 31 to a suitable electro power source, 65 a switch 32 being provided on the handle 13, preferably on the inside of the handle as indicated in Fig. 1 for the purpose of closing the electro circuit to make the electro-magnets in the arms 19 active for the purposes hereinafter described.

The outer end of the body 12 of the riveting tool is threaded as indicated at 34 upon which is threaded a nut 35 held in place by means of a lock nut 36. Interposed between 75 the nut 35 and the outer side of the collar 18 is a coiled compression spring 37, a circular flange 38 being formed on the outer side of the collar 18 to form a seat for the end of the spring engaging the collar and preventing dislodgment of the same during the operation of the riveting tool. 40 and 41 designate two plates upon which the work is being performed, 42 a rivet and 43 a bucking tool held against the plate on the opposite side of the same to the hammer 14.

In the form shown in Fig. 3 the yoke is used for the purpose of supporting the bucking tool, it being understood that the yoke constructed as above described may also be used for supporting the bucking tool and thereby reducing or absorbing the impact ordinarily received by the bucking tool during the operation of riveting.

The device above described operates in 95 the following manner:

When a rivet is to be headed the riveting tool is placed in position with the hammer over the rivet and with the feet 20 resting against the plates to be riveted. The switch 32 is then closed and the feet become magnetized a sufficient degree to hold the yoke firmly against the plates during the riveting operation. The air is then admitted to the tool by operation of the lever 16 and the riveting action takes place, the tool being held against the rivet by the person operating the device, but the tool being held or supported on the spring 37. The shocks caused by the impact of the hammer 14 are 116

absorbed to a large extent by the spring 37 thereby relieving the operator from the force of the shocks which are ordinarily directly received by the person holding the 5 tool.

It is to be noted that considerable space is left between the body of the riveting tool and the inside of the collar 18 so that the tool may be moved to adjust the same without removing the yoke from the plate. 10

When the riveting operation has been finished the air is shut off, the riveting action being stopped, the switch 32 is opened and the yoke may be readily detached from 15 the plate and moved into position for the next rivet.

I claim as my invention:—

- 20 1. A riveting device consisting of a supporting member, a riveting tool extending freely through and elastically supported in the supporting member, and means whereby said supporting member is electro-magnetically held against the work during the riveting operation.
- 25 2. A riveting device comprising a supporting device consisting of a ring, legs formed on said ring, a coil in the end of each leg, a riveting tool extending freely

through the ring, elastic means for supporting the tool in said ring, and means for introducing an electric current to said coils. 20

3. A riveting device arranged to absorb shocks comprising a supporting member, legs on said supporting member, a coil in the end of each leg, means for energizing 35 said coils, a riveting tool extending freely through the supporting member, threads on the outer end of said riveting tool, a nut on said threads, and a coiled spring interposed between said nut and said supporting 40 member.

4. A riveting device arranged to absorb shocks comprising a supporting member, legs on said supporting member, a coil in the end of each leg, means for energizing 45 said coils, a riveting tool extending freely through a central opening in the supporting member, a removable abutment on the inner end of the tool, and a coiled spring about said tool interposed between said abutment 50 and the supporting member.

In testimony whereof, I have hereunto set my hand at Los Angeles, California, this 13th day of June, 1918.

NELS H. HASSEL.
